UNITED STATES PATENT OFFICE.

JOSEPH A. FURTADO, OF HALF MOON BAY, CALIFORNIA.

GOLD-WASHING MACHINE.

1,241,954.

Specification of Letters Patent.

Patented Oct. 2, 1917.

Application filed January 5, 1917. Serial No. 140,808.

To all whom it may concern:

Be it known that I, JOSEPH A. FURTADO, a citizen of the United States, residing at Half Moon Bay, in the county of San Mateo 5 and State of California, have invented new and useful Improvements in Gold-Washing Machines, of which the following is a specification.

This invention relates to gold washing machines, and it has for its object to produce a device of this class which will be simple in construction, convenient in operation and by the use of which gold bearing sand and gravel may be effectively treated for the extraction of gold.

A further object of the invention is to produce a device of the class described whereby the use of water will be economized.

A further object of the invention is to produce a device of the class described, the parts of which are simple in construction, easily assembled and which may be economically operated either manually or by power derived from any convenient source.

With these and other ends in view which will readily appear as the nature of the invention is better understood, the same consists in the improved construction and novel arrangement and combination of parts 30 which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—

Figure 1 is a top plan view of a machine constructed in accordance with the invention.

Fig. 2 is a side elevation of the same.

Fig. 3 is a vertical sectional view taken on the line 3—3 in Fig. 1.

Fig. 4 is a horizontal sectional view taken on the line 4—4 in Fig. 3.

Fig. 5 is a sectional detail view taken on the line 5—5 in Fig. 4.

Corresponding parts in the several figures are denoted by like characters of reference.

The frame 15 of the improved machine may be constructed in any suitable manner and of any suitable material, angle iron or steel being, however, deemed preferable on account of its qualities of lightness, strength and rigidity. The frame is provided with bearings for four equidistant vertical shafts 16 each having at its upper end a crank 17, 55 said cranks all radiating in one direction. Each shaft 16 carries a gear wheel 18, the four gear wheels meshing with a master wheel 19 which may be driven in any convenient manner by manual or other power. 65 If preferred, the driving energy may be applied to one of the vertical shafts 16 and be transmitted through the master wheel to the remaining vertical shafts so that the several vertical shafts will be synchronously rotated 70 at equal speed.

A cylindrical casing 20 is provided with circumferential reinforcing bands 21, 22 carrying equidistant tubular bearings 23 engaged by the cranks 17 so that, by the rotation of the shafts 16, a gyratory motion will be imparted to the cylindrical casing.

The casing 20 carries at its upper end a sieve comprising a perforated bottom member 24 and a flaring wall member 25, the latter having an outlet 26 provided with a spout 27. The bottom member 24 has a centrally disposed imperforate depression or shallow pan 28.

Mounted within the cylindrical casing 20 and connected circumferentially with the wall thereof are flat conical pans 29 of which any desired number may be used, according to the dimensions of the casing, two such pans having been shown in the illustration, and each of said pans being provided at its apex with an opening 30. Suspended above each pan 29 by means of hangers 31 is a flat conical diaphragm 32, said diaphragm being of a diameter less 85 than the interior diameter of the casing 20, thus permitting material to overflow each diaphragm circumferentially to the pan below. The lowermost pan 29 has secured to the underside thereof a receptacle 33, the same being secured directly beneath the opening 30. The receptacle 33 has a laterally extending discharge tube or spout 34, and the bottom member 35 of said receptacle

is inclined in the direction of the central portion thereof which is provided with a well 36 having a screw cap 37.

Each of the pans 29 has a riffle 38 of arcuate shape near the marginal edge thereof, said riffle having an inclined bottom which at one end merges with the surface of the pan and which at the other end communicates with a well 39 having a screw cap or other convenient detachable closure 40. The riffles 38 may each extend through an arc of any desired degree. In the drawings the said riffles have been shown as extending through an arc of about 180 degrees, but the extent thereof may be varied as far as desired.

The wall member 25 which bounds the sieve at the top of the casing is provided with inwardly extending arms or brackets 41 supporting a deflector 42 which is arranged adjacent to and in spaced relation to the outlet 26, the purpose of said deflector being to partly obstruct the outlet, thereby preventing an excess of material from being discharged therethrough.

From the foregoing description, taken in connection with the drawings hereto annexed, the operation and advantages of this invention will be readily understood by those skilled in the art to which it appertains. The material from which gold is to be separated is placed in the sieve bounded by the wall 25, and is subjected to an inflow of water from any suitable source, while the casing 20 is being gyrated at a speed which may be controlled in any well known manner. It is obvious that the speed may be varied according to the nature of the material that is to be operated upon and other conditions. By the centrifugal action thus set up, the large gravel or other particles in the sieve will be thrown in the direction of the wall 25 and expelled through the outlet 26. Some of the values will settle in the pan 24, while values that are not separated in this manner will pass through the sieve along with the relatively fine sand and gravel, being deposited on the cone-shaped diaphragm immediately beneath the sieve and permitted to overflow the edge of the latter on to the pan 29 directly below. As material accumulates in this pan, the constant agitation to which it is subjected will tend to throw the values which constitute the heaviest portion in the direction of the wall of the casing 20 where the values gradually accumulate in the riffle 38 over which they are carried to the well 39. The material which escapes from the uppermost pan 29 through the opening 30 at the center thereof drops upon the diaphragm 32 next below which it overflows, passing from thence to the next pan 29 where the operation is repeated. As has been previously stated, the cylindrical casing may contain as many dia-

phragms and pans as may be desired. From the lowermost pan the material passes through the opening 30 to the receptacle 33 from which the refuse will escape through the spout 34, while the last remaining values are permitted to settle in the well 35, the values being readily removed from the several wells by removing the caps or closures thereof, while any values settling in the shallow pan 24 may be removed from the top of the same. The improved machine is simple in construction, economical and efficient in operation, and is capable of being operated either manually or by power derived from any suitable source.

Having thus described the invention, what is claimed as new, is:

1. In a device of the class described, a cylindrical casing, a sieve at the top of the casing having a wall provided with an outlet, and overflow diaphragms and separating pans arranged in alternate order below the sieve, each pan having an arcuate inclined riffle; and a well with which the lower ends of the riffles in the pans communicate.

2. In a device of the class described, a cylindrical casing, a sieve at the top of the casing having a wall provided with an outlet, and overflow diaphragms and separating pans arranged in alternate order below the sieve, each pan having an arcuate inclined riffle; a well with which the lower ends of the riffles in the pans communicate, and a detachable bottom closure for said well.

3. In a device of the class described, a cylindrical casing, a sieve at the top of said casing, said sieve having a centrally disposed well, overflow diaphragms and separating pans arranged in alternate order below the sieve, said diaphragms and pans being substantially cone-shaped and the pans having central openings, each pan being provided near the marginal edge thereof with an arcuate riffle having a downwardly inclined bottom portion, and a well at the low end of such riffle.

4. In a device of the class described, a cylindrical casing, a sieve at the top of said casing, said sieve having a centrally disposed well, overflow diaphragms and separating pans arranged in alternate order below the sieve, said diaphragms and pans being substantially cone-shaped and the pans having central openings, each pan being provided near the marginal edge thereof with an arcuate riffle having a downwardly inclined bottom portion, and a well at the low end of such riffle, the lowermost pan having secured to the underside thereof a receptacle provided with an outlet spout at the margin thereof and with a centrally disposed well.

5. In a device of the class described, a cylindrical casing, means for supporting the casing and for imparting thereto a gyroscopic movement, a sieve at the top of the

casing, said sieve having a wall provided with an outlet, a conical pan within the casing connected marginally with the wall thereof, said pan having an arcuate riffle 5 with an inclined bottom and a well at the low end of the bottom portion, said pan being also provided with a central opening, a conical overflow diaphragm supported above

the pan, hangers supporting the diaphragm, and a receptacle beneath the pan to receive 10 material through the central opening at the apex thereof, said receptacle having an outlet spout at the margin thereof and a centrally disposed well.

In testimony whereof I affix my signature. 15
JOSEPH A. FURTADO.
